(57) **CLAIM**

The ornamental design for a DC charging gun, as shown and described.

DESCRIPTION

FIG. 1 is a perspective view of a DC charging gun design showing our new design.

FIG. 2 is a front view of a DC charging gun, shown enlarged in scale.

FIG. 3 is a rear view of a DC charging gun, shown enlarged in scale.

FIG. 4 is a left side view of a DC charging gun.

FIG. 5 is a right side view of a DC charging gun.

FIG. 6 is a top view of a DC charging gun.

FIG. 7 is a bottom view of a DC charging gun; and,

FIG. 8 is an enlarged view of a DC charging gun taken from the circle part in FIG. 2.

The broken lines depict portions of the DC charging gun that forms no part of the claimed design.
